UNITED STATES PATENT OFFICE

96,856

DESIGN FOR AN AUTOMOTIVE VEHICLE HEATER

Harry Rose, Wyandotte, Mich.

Application March 27, 1935, Serial No. 56,075

Term of patent 7 years

To all whom it may concern:

Be it known that I, Harry Rose, a citizen of the United States, residing at Wyandotte, in the county of Wayne and State of Michigan, have invented a new, original, and ornamental Design for Automotive Vehicle Heaters, of which the following is a specification, reference being had to the accompanying drawing forming part thereof.

Fig. 1 is a perspective view of an automotive vehicle heater showing my new design; and

Fig. 2 is a side elevational view of the automotive vehicle heater, portions of the bracket elements being broken away for convenience of illustration.

I claim:

The ornamental design for an automotive vehicle heater, as shown.

HARRY ROSE.
